Patented Jan. 13, 1920.

UNITED STATES PATENT OFFICE.

WILLIAM S. GUTHRIE, OF TERRELL, TEXAS.

CARBURETER.

1,328,042.

Specification of Letters Patent. Patented Jan. 13, 1920.

Application filed January 26, 1917. Serial No. 144,648.

To all whom it may concern:

Be it known that I, WILLIAM S. GUTHRIE, a citizen of the United States, residing at Terrell, in the county of Kaufman and State of Texas, have invented certain new and useful Improvements in Carbureters, of which the following is a specification.

My invention relates to the control of the combustible mixture for internal combustion engines, and the primary object of the invention is to provide economical mixtures when the engine is running under normal conditions at the intermediate speeds.

The invention relates particularly to a carbureter for controlling the quality of the combustible mixture for internal combustion engines, for example those of automobiles, where the load is frequently varied, such engines requiring a wide range of variation in the proportion of fuel and air in order to efficiently and economically supply the demand made upon them.

Pleasure automobiles are usually run at speeds ranging from 10 to 35 miles per hour, and a lean mixture is efficient at these speeds on reasonably good roads. This invention is intended to provide the maximum mileage on fuel for automobiles when running at these intermediate speeds under normal conditions, such as when the roads are reasonably good and the load is comparatively light.

To accomplish the object of this invention in a type of carbureter as shown in the drawing, the discharge end of an auxiliary air passage is positioned in such manner that it opens into the mixture passage at a point beyond the throttle when the latter is in a nearly closed position so it will supply uncared for air to the mixture passage at the intermediate engine speeds.

With the above and other objects in view, the invention consists in the novel and useful provision, formation, construction, combination, association and relative arrangement of parts, shown in the drawing, and finally pointed out in the claims.

The drawing, which is partly in section, shows a carbureter equipped with my invention and attached to the engine 1, the latter being conventionally shown and being somewhat reduced in size.

Referring to the drawing, the throttle valve 49 is positioned in the mixture passage and controls the flow of explosive mixture from the carbureter 45 to the engine in the

usual way. The port 52 forms an auxiliary air passage that supplies air to the mixture passage at a point beyond the throttle when the latter is partially opened for the intermediate engine speeds.

It is necessary to make the auxiliary air passage 52 less operative for the slow engine speed in order that less air will flow through the same at that time; and it is also desirable to avoid the use of any additional moving parts. The auxiliary air passage is, therefore, preferably positioned in the wall of the carbureter body adjacent the throttle so that, when the latter is normally closed for the slow engine speed, it restricts the communication between the port 52 and the strong suction beyond the throttle and (when a thin throttle disk such as shown is used) opens the discharge end of said port into the mixture passage on the air intake side of the throttle. The position of the auxiliary air passage with relation to the throttle may be varied somewhat from that shown in the drawing, as it may be desirable to have the auxiliary air passage so arranged that it will supply some air beyond the throttle when the latter is normally closed for the slow engine speed, and an increased amount as the throttle is opened for the intermediate speeds.

It will be apparent that, the throttle, as it approaches the port 52 inclosing, serves as a shutter valve to vary the communication of the auxiliary air passage with the mixture passage beyond the throttle without the use of additional moving parts.

The air pressure in the mixture passage on the air intake side of the throttle in this type of carbureter is practically atmospheric when the throttle is closed for slow engine speed, and very little air, if any, will then flow through the auxiliary air passage into the mixture passage on the air intake side of the throttle.

This control of the auxiliary air passage that is, by using a thin throttle disk, is preferably used in connection with carbureters having means for supplying hydrocarbon fuel to the mixture passage at a point beyond the throttle for the slow engine speeds, as by a fuel feed jet 51, so the vent action of the auxiliary air passage on the air intake side of the throttle will not interfere with the normal slow speed mixture.

The auxiliary air passage 52 may be sufficiently large to insure the passage of ade-

quate air to provide the leanest possible mixture for the intermediate speeds.

A manually actuated valve 55, which is not necessary when the passage 52 is calibrated to correspond to the particular engine, may be provided to control the flow of air through the auxiliary air passage. This valve is provided with screw threads so that the turning of the same will open or close the auxiliary air passage as may be desired. This valve 55 may be turned in to entirely close off the auxiliary air supply to run the engine at times when a lean mixture is not efficient, such as may be the case in cold weather before the engine is warmed up to a normal heat. The manually controlled valve makes it an easy matter to readily vary the quality of the explosive mixture at any time in the operation of the engine. Various other forms of manually controlled valves may be employed to control the flow of air through the auxiliary air passage.

When the throttle is fully opened for the maximum power of the engine, the auxiliary air passage 52 may continue to supply some air to the mixture passage, and it is prevented from impairing the power under these conditions by restricting the air inlet to the mixing chamber of the carburetor, as by restricting the Venturi passage 47 so it supplies no more additional air than required for developing the maximum power. In other words, the difference in the suction in the venturi and at the port 52 at the high speeds decreases the flow of auxiliary air through the passage 53-52, because the venturi then demands practically all the air then entering the air passage 46. The fuel nozzle 48 will supply fuel for the maximum power of the engine in the usual way.

A by-pass passage is preferred to convey air to the auxiliary air passage 52 from the main air inlet passage 46 of the carburetor, as by a conduit 53. The point of connection of the by-passage 53 with the main air inlet passage is anterior to the fuel nozzle 48 and beyond the choke valve 54. The auxiliary air thus supplied to the auxiliary passage 52 will be non-hydrocarbon fluid, or uncarbureted air, because it does not pass by the fuel nozzle, and it will be of the same temperature as that supplied to the main air inlet passage. The auxiliary air passage may obviously be of any desired shape in cross-section.

When internal combustion engines are equipped with economical carburetors they are usually hard to start, especially in cold weather, unless some means are employed to abnormally enrich the mixture when starting. In the present case a choke valve 54 is employed for this purpose, but it will be understood that any other known enriching means may be employed.

With the choke valve 54 positioned ante-

rior to the by-pass passage 53 as shown in the drawing, it will retard the flow of air to the auxiliary air passage when closing the same for starting the engine, and this prevents the auxiliary air passage from admitting air to impair the starting of the engine.

A structure of the character shown and described is especially desirable for the reason that the auxiliary air passage is controlled with but few moving parts, but the invention is intended to cover a wide range of structures in addition to that shown in the drawing. I do not, therefore, wish to be limited except as indicated by the subjoined claims.

I claim:—

1. A carburetor comprising a body having a carbureting passage provided with an oscillating throttle valve, means for supplying fuel and air to said passage, an auxiliary air passage independent of the fuel supply arranged so it discharges the greatest volume of air to the carbureting passage at a point beyond the air intake side of the throttle when the latter is partly closed and arranged so that the throttle valve in closing passes between the outlet of the auxiliary air passage and the engine.

2. A carburetor having a body with a mixing chamber therein, means for supplying fuel to the mixing chamber, an air intake passage, a venturi forming a restricted passage between the mixing chamber and the air intake passage, a throttle in the mixing chamber, an auxiliary air passage extended from said air inlet passage anterior to said venturi into the mixing chamber beyond the venturi, said auxiliary air passage being so arranged that it by-passes the throttle when the latter is nearly closed, and also being so arranged that it normally supplies no carbureted air at any speed of the engine.

3. A carburetor comprising a body having a carbureting passage provided with an oscillating throttle valve, means for supplying fuel and air to said passage, an auxiliary air passage independent of the fuel supply arranged so it discharges the greatest volume of air to the carbureting passage at a point beyond the air intake side of the throttle when the latter is partly closed and arranged so that the throttle valve in closing passes between the outlet of the auxiliary air passage and the engine, and an idling jet communicating with the source of fuel supply and discharging into the carbureting passage beyond the air intake side of the throttle.

4. A carburetor having a body with a mixing chamber therein, means for supplying fuel to the mixing chamber, an air intake passage, a venturi forming a restricted passage between the mixing chamber and

- the air intake passage, a throttle in the mixing chamber, an auxiliary air passage extended from said air inlet passage anterior to said venturi into the mixing chamber beyond the venturi, said auxiliary air passage being so arranged that it by-passes the throttle when the latter is nearly closed, and also being so arranged that it normally supplies no carbureted air at any speed of the engine, and an idling jet communicating with the source of fuel supply and discharging into the mixing chamber beyond the air intake side of the throttle.
5. A carbureter having a body with a mixing chamber therein, an air passage directing air to the mixing chamber, means for supplying fuel to the mixing chamber, an auxiliary air passage, communicating with the first named air passage and by-passing the throttle when the latter is nearly closed, said auxiliary air passage being so arranged that it normally supplies no carbureted air when idling the engine at the slowest speed,
- 10
- 15
- 20
- and the throttle being so arranged that in closing it retards the suction on the auxiliary air passage.
- 25
6. A carbureter, a fuel feeding device, a throttle valve, an air passage directing air past said fuel feeding device, an auxiliary air passage communicating at two points with said first mentioned air passage and by-passing said fuel feeding device and said throttle valve when the latter is partly open, said auxiliary air passage opening into the first named air passage at a point adjacent the closed position of the throttle valve, the auxiliary air passage being so arranged that it supplies no hydrocarbon fuel at any speed of the engine.
- 30
- 35
- In testimony whereof I have signed this specification in the presence of two subscribing witnesses.

WILLIAM S. GUTHRIE.

Witnesses:

C. T. McCLEUNG,
C. H. WIELAND.

It is hereby certified that in Letters Patent No. 1,328,042, granted January 13, 1920, upon the application of William S. Guthrie, of Terrell, Texas, for an improvement in "Carbureters," an error appears in the printed specification requiring correction as follows: Page 1, line 88, for the word "inclosing" read *in closing*; and that the said Letters Patent should be read with this correction therein that the same may conform to the record of the case in the Patent Office.

Signed and sealed this 10th day of February, A. D., 1920.

[SEAL.]

M. H. COULSTON,
Acting Commissioner of Patents.
